CLAIM

The ornamental design for a contactor housing, as shown and described.

DESCRIPTION

FIG. 1 is a front left perspective view of a contactor housing in accordance with the design;

FIG. 2 is a rear right perspective view thereof;

FIG. 3 is a left side elevation thereof;

FIG. 4 is a right side elevation thereof;

FIG. 5 is a front elevation thereof;

FIG. 6 is a rear elevation thereof; and,

FIG. 7 is a top plan view thereof, the bottom plan view thereof is not illustrated as it forms no part of the claimed subject matter.

It is to be understood that the portions of the contactor housing shown in broken line in the accompanying figures show unclaimed subject matter and form no part of the claimed subject matter.
